UNITED STATES PATENT OFFICE.

LEYEL C. HALL, OF PORTLAND, OREGON.

IMPULSE STARTER AND IGNITION BOOSTER FOR INTERNAL-COMBUSTION ENGINES.

Application filed January 18, 1922. Serial No. 530,108.

To all whom it may concern:

Be it known that I, LEYEL C. HALL, a citizen of the United States, residing at Portland, in the county of Multnomah and State of Oregon, have invented certain new and useful Improvements in Impulse Starters and Ignition Boosters for Internal-Combustion Engines, of which the following is a specification.

- 10 This invention relates to attachments for internal combustion engines and is an improvement of my pending application, filed March 18, 1921, Serial No. 453,259, and the primary object of the present invention is 15 the provision of a novel combined means for starting an internal combustion engine and for insuring and facilitating the firing of the charge in internal combustion engines utilizing a low grade fuel, such as kerosene.
- 20 Another object of the invention is the provision of a novel device, for associating with the spark plug opening of each cylinder of an internal combustion engine, embodying a supplemental firing chamber of novel 25 construction, and ignition means of novel construction for firing the charge in said supplemental firing chamber, and means for feeding compressed air and high test fuel to the supplemental firing chamber, the 30 compressed air being utilized in connection with high test fuel for starting the engine, means being provided for stopping the flow of the compressed air after the engine has once been started.
- 35 A further object of the invention is the provision of means for permitting the carburetion of high test fuel in the device as the same enters the supplemental firing chamber, whereby the necessity of providing 40 an auxiliary carburetor for the high test fuel is eliminated, the air for mixing with the high test fuel being under control of a valve, which is normally held upon its seat when compressed air is being supplied to 45 the device for starting purposes.

A still further object of the invention is the provision of a novel starting and ignition booster for internal combustion engines embodying a casing having a supplemental 50 firing chamber therein, a pair of independent insulated electrodes disposed therein, and an intermediate electrode grounded to the casing, an independent circuit for each insulated electrode, one of the circuits being utilized for starting the engine and the

other circuit being utilized for running the engine after the same has been started.

A still further object of the invention is the provision of an improved starting and ignition booster for internal combustion engines embodying a firing chamber, a fuel inlet, an auxiliary air inlet for permitting air to combine with the fuel when the engine is running under normal conditions, and a compressed air inlet for combining with the fuel during the initial starting of the engine.

A still further object of the invention is the provision of a device of the above character which can be readily disassembled when necessary or desirable, in order to permit the easy cleaning thereof and the replacement of parts when worn or broken.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a vertical section through an internal combustion engine showing the improved attachment applied thereto.

Figure 2 is a top plan view of the improved attachment applied to a cylinder of an internal combustion engine.

Figure 3 is an enlarged longitudinal section through the improved attachment.

Figure 4 is a section through the attachment taken on the line 4-4 of Figure 3.

Figure 5 is an enlarged detail perspective view of the valve member for controlling the entrance of the fuel and the compressed air into the attachment.

Figure 6 is a plan view of the coupling or union utilized for connecting the parts of the attachment together.

Figure 7 is a vertical section through the coupling or union taken on the line 7-7 of Figure 6, and

Figure 8 is a fragmentary elevation of the feed pipe for compressed air showing the valve arranged therein and the switch for controlling the circuit through one of the ignition devices, the switch being shown partly in section.

Referring to the drawings in detail, wherein similar reference characters designate corresponding parts throughout the several views, the letter A indicates the in-

ternal combustion engine, and B, the improved attachment for starting the engine and for facilitating the exploding or ignition of low grade fuel when used therewith.

- 5 The engine A may be of the usual or any preferred character and as shown includes a plurality of cylinders 10 provided with the usual inlet ports 11, and valves 12 for controlling the flow of fuel therethrough.
- 10 As shown, the cylinders 10 have reciprocably mounted therein in the usual manner the pistons 13. The inlet port 11 has communicating therewith the usual inlet manifold 14 which has communicating therewith an ordinary carburetor 15. The carburetor 15 is supplied with fuel from the tank 16 which is adapted to contain low grade fuel, such as kerosene or the like. The head 17 of each cylinder 10 is provided with the usual spark plug opening 18, in which, in this instance, is adapted to be fitted the improved attachment B.

The improved attachment B comprises a housing 20 for each one of the cylinders 10, a relatively small auxiliary fuel tank 21, and a tank 22 for containing compressed air for facilitating the starting of the engine. The tank 21 for containing the high test gasoline is connected by means of a lead pipe 23, with a longitudinally extending manifold pipe 24, which has connection with all of the housings 20 as will be hereinafter more fully apparent as the description proceeds. The fuel feed pipe 23 may have interposed therein a suitable valve 25, for controlling the flow of fuel therethrough, and this pipe is of course adapted to feed the fuel of a relatively high grade. The compressed air tank 22 is connected by a pipe 26 with the manifold pipe 27, which is in turn connected by a means which will be hereinafter more fully described, with all of the housings 20. A valve 28 is interposed in the lead pipe 26 of the compressed air, in order to control the passage of the compressed air through the pipe, and this valve including a sliding valve stem having a head 29 and upon the operation of the valve, a circuit is adapted to be closed for igniting a charge in each one of the housings as will also be hereinafter more fully described.

Each of the housings 20 include an upper section 30 and a lower section 31 which is adapted to be connected with each cylinder head. The lower section 31 includes a threaded nipple 32, which is threaded within the spark plug opening 18 of the cylinder head 17, and this nipple has an inwardly extending tapered bore 33. A shoulder 34 is formed on the upper end of the nipple and is adapted to be engaged by a coupling 35, which is shaped to conform to the upper end of the nipple. This coupling 35 is provided with outwardly extending ears 36, which are adapted to receive bolts 37 ex-

tended through ears 38 formed on the upper section 30, which will now be described.

The upper section 30 has formed therein a firing chamber 39 at its forward end, and this chamber is provided with a flared passageway 40 which is adapted to communicate with the tapered bore 33 of the lower section 31. The upper end of the section 30 is provided with a longitudinally extending tubular casing 40, through which the fuel, the compressed air, and the auxiliary air is adapted to flow into the firing chamber 39, and this casing communicates with the upper end of the firing chamber. The casing 40 is provided with means which will be herein-after more fully described for controlling the flow of fuel and air therethrough and for preventing the products of combustion from entering into the same. The section 40 has also formed thereon the radially extending, downwardly inclined sleeves 41 and 42, in which are adapted to be positioned the insulated electrodes 43 and 44. The inner ends of the sleeves 41 and 42 communicate with the firing chamber 39 at a point substantially intermediate its ends. The sleeves 41 and 42 have the bores thereof enlarged intermediate their ends to provide shoulders 45, on which are adapted to rest the insulated body portions 46 of the electrodes 43 and 44. The insulated bodies 46 of the electrodes 43 and 44 are provided which shoulders 47 for fitting upon the shoulders 45 and the shoulders 47 are held on the shoulders 45 by suitable retaining or packing nuts 48. The electrode 43 has electrically connected thereto the ordinary wire 49 leading from the ordinary ignition system, while the electrode 44 has connected thereto a wire 50 leading from an auxiliary ignition system which includes a suitable battery 51 and coil 51'. This ignition system is controlled by a switch 52, which is operated by the compressed air valve 28, as heretofore stated, and which will be hereinafter more fully described. An adjustable electrode 53 is carried by the section 30 and is disposed opposite the electrodes 43 and 44. This electrode 53 is grounded to the housing 20 and consequently to the frame of the engine similar to the shell of an ordinary spark plug. The electrode 53 is held in any preferred position against displacement by means of a locking nut 54. When the regular ignition system is in use, it will be seen that a double spark will be provided as the spark will jump from the electrode 43 to the electrode 44 and then to the ground electrode 53. The forward end of the casing 40 is closed by a threaded plug 55, which permits the convenient cleaning of the firing chamber when so desired.

The rear end of the sleeve or casing 40 is closed by a removable head 56, which is pro-

- vided with a central passageway 57. This passageway 57 has communicating with the upper end thereof a pipe 58, which is in turn connected to the manifold feed pipe 24.
- 8 The inner end of the pipe 58 may be provided with a valve seat 59 on which is adapted to normally seat a ball 60 when compressed air is permitted to flow into the head as will be hereinafter more fully set forth.
- 10 An inwardly extending passageway 61 is formed in the head, and this passageway communicates intermediate its ends with the passageway 57, and this passageway 61 constitutes the inlet for compressed air and has 15 threaded therein a relatively short pipe 62, which communicates with a compressed air manifold or lead pipe 27. The inner end of the relatively short pipe 62 may be provided with a valve seat, on which is adapted to 20 normally seat a ball valve 63, which is retained in its normal seating position by means of an expansion coil spring 64, which is disposed within the passageway 61. Thus the escape of air through this pipe is normally prevented, and this valve also acts to 25 prevent the passage of fuel into the same, when the flow of air through the manifold feed pipe 27 is cut-off. Extending directly through the head 56 and into the casing is 30 the control or metering plug 65. The control or metering plug 65 is provided with an inwardly extending bore 66, and with radially extending passageways 67 which communicate with the passageways 57. The outer 35 end of the control plug 65 is provided with a nut head 68, whereby the same may be conveniently adjusted by a wrench or the like. It can be seen that by adjusting the plug, more or less of the radially extending passageways 67 will be uncovered, thus controlling the amount of fuel entering into the casing 40. The inner end of the metering plug is provided with a valve seat 69 and a conical valve 70 is adapted to fit on the seat 45 and extend into the bore 66 thereof. The inner end of the valve 70 is provided with a guide sleeve 71 which is slidably mounted within the hollow stem 72 of a main control valve 73, which is normally held on a seat 50 74 formed on the inner end of the casing 40 by means of an expansion spring 75. This expansion spring 75 is disposed directly in the hollow stem 72 of the valve and engages at one end against a stationary pin 76, which 55 is threaded through the casing 40 and extended through suitable slots 77 formed in the stem 72 for that purpose. The opposite end of the spring 75 bears against a cross cotter pin 78, carried by the stem. A guide 60 80 is provided for the stem 72 and this guide may be provided with an oil opening for permitting of the lubrication thereof. A suitable oil plug 81 can be threaded into the casing 40 into engagement with the guide 65 and serves the dual function for permitting the lubrication of the guide and the holding of the same against displacement. An expansion spring 82 is disposed in the sleeve 71 of the valve 70 and this spring also engages the cotter pin 78 and this spring tends to normally hold the conical valve 70 on its seat and in the bore 66 of the control plug 65. Suitable guide slots 71' are formed in the sleeve 71 of the valve 70 for the cotter pin 78 and these slots permit movement of the valve 70 in relation to the seat.
- The stem 72 of the valve 73 is provided adjacent each end thereof with entrance openings 83 for permitting the flow of fuel and air therethrough.
- The casing 40 adjacent to the rear end thereof is provided with a depending body 85 in which is threaded a tube 86, which permits the entrance of air into the casing 40. The inner end of the tube is provided with a valve seat for the reception of a ball valve 87. A wire screen cap 88 can be provided for housing the ball valve to prevent displacement thereof.
- The switch 52, utilized for controlling the circuit through the auxiliary ignition means, includes a base plate 91 formed of insulating material which may have embedded therein spaced contacts 92 and 93. The contact 92 may have connected thereto in any preferred manner, a resilient arm 94' which is adapted to overlie the contact 93. In order to close the circuit when the compressed air is used for starting purposes, the head or handle of the valve is provided with an outwardly extending arm 94, which is provided with a hooked end 95, for engaging the resilient arm 94'. Any suitable type of switch can be provided for closing the circuit through the auxiliary ignition system and this switch has been merely shown by way of example and the switch can be manually operated or operated in any preferred manner by the stem of the air valve or in a manner as shown in the drawings.
- In operation of the improved attachment, when it is desired to start the engine, the valve 25 is opened, and the fuel from the high test tank 21 is permitted to flow by gravity into the passageway 57. After the valve 25 has been opened, the compressed air valve 28 is opened by depressing the head 29, which will permit the air to flow through the pipe 26 and unseat the valve 63 and flow into the passageway 57. The forcible entrance of the compressed air to the passageway 57 will carry the fuel through the openings 67, through the bore 66 of the metering tube and forces the valve 70 off of its seat, the valve 73 from off of its seat, and the mixture will then flow into the firing chamber 39 into the cylinders of the engine. Upon release of the valve handle 29, the hooked end 95 of the arm 94 will flex the resilient arm 94' and force the same

into engagement with the contact 93, thus closing the circuit through the auxiliary ignition system and causing a spark through the electrode 44 and the electrode 53, which 5 will, of course, ignite the charge or mixture in the firing chamber 39 and in the cylinders. When the charge is fired, the pistons in the cylinders will be operated in proper sequence, which will draw the fuel into the 10 cylinders in the ordinary manner and thus permit the starting of the engine.

After the engine has started running, the improved attachment will operate in the following manner. The pistons operating 15 in the cylinders will create a sufficient suction within the firing chambers 39 to cause the unseating of the valves 73 and 70 and to suck the fuel from the passageway 57 and air from the auxiliary passageway or tube 20 86. Simultaneous with the sucking of the charge into the auxiliary firing chamber 39, a charge will be drawn into the cylinders in the ordinary manner through the manifold 14 and the ordinary carburetor 15. 25 Upon the closing of the circuit of the ordinary ignition system, sparks from the electrodes 43 and 53 will, of course, fire the charge in the firing chamber 39, which will project a relatively large sheet of flame into 30 the cylinder, thus causing the firing of a charge within the cylinders. This sheet of flame tends to compress the ordinary charge within the cylinders and thus increase the likelihood of the firing thereof. When the 35 engine is operating under normal conditions, the valve 28 is of course, held in closed position, so as to prevent the flow of compressed air into the attachment. It can be seen that when the compressed air is permitted 40 to flow into the casing 40, the valve 60 will be forced upon its seat and thus prevent the flow of compressed air into the fuel supply manifold.

From the foregoing description, it can 45 be seen that an improved device has been provided for not only facilitating the igniting of fuel of the heavy type, such as kerosene, but also for starting the engine.

Changes in details may be made without 50 departing from the spirit or scope of this invention; but,

I claim:

1. A combined starting and charge igniting device for internal combustion engines, 55 comprising a casing having direct communication with the cylinder heads of an engine, a firing chamber in the casing, means for introducing fuel and compressed air in the casing, and means for firing the charge in said casing.

2. A combined starting and charge igniting device for internal combustion engines comprising a casing having direct communication with the cylinders of an internal combustion engine, a firing chamber in each cas-

ing, fuel and compressed air supplying means communicating with the casing, valves for controlling the flow of fuel and compressed air, and means for firing a charge in the firing chamber.

3. A starting and igniting device for internal combustion engines comprising a casing having direct communication with the cylinders, of an internal combustion engine, a firing chamber in the casing, an igniting device positioned in the firing chamber, fuel and compressed air supplying means communicating with the casing, valves for closing the passageway for fuel and compressed air, and an auxiliary air inlet communicating with the casing.

4. In a device for facilitating the use of low grade fuel in internal combustion engines and for starting internal combustion engines, the combination with an internal combustion engine including cylinders, an explosion chamber in each one of the cylinders, an inlet port for each one of the cylinders, an inlet valve disposed in each port for controlling the flow of the charge through the ports, means for feeding low grade fuel through said ports, of a casing including a relatively small explosion chamber, a fuel inlet port communicating with the chamber, means for feeding a high test fuel to said port, a compressed air inlet port, means for feeding compressed air through said port, and an ignition device disposed in said explosion chamber.

5. In a means for facilitating the use of low grade fuel in internal combustion engines and for starting internal combustion engines, the combination with internal combustion engines including cylinders having openings therein for receiving the usual spark plugs, an inlet port for each cylinder, a valve for controlling the flow of fuel through each inlet port, means for feeding low gravity fuel through the ports, and a casing detachably fitted in each one of said openings including a relatively small explosion chamber, a tapered bore for communication with the explosion chamber of each cylinder, an inlet port formed in the casing for communicating with the explosion chamber therein, an inlet port for compressed air formed in the casing and communication with the explosion chamber, a valve for normally closing the inlet port for the compressed air, and an igniting device arranged in the explosion chamber, and a normally closed valve for preventing the entrance of the fuel and air into the firing chamber.

6. The combination with an internal combustion engine cylinder including a head having an opening therein, an inlet port, a valve for controlling the flow of fuel through said inlet port, a fuel tank, means for connecting the fuel tank with the inlet port, a

- casing having a firing chamber therein communicating with said opening, an ignition device carried by said casing for firing the charge in said chamber, a valve seat formed in the casing above the explosion chamber, a sliding valve normally arranged to fit upon said seat, a fuel inlet port formed in the casing in rear of said seat, and an auxiliary air inlet formed in said casing in rear of said seat.
7. The combination with a cylinder including an opening having a head therein, an inlet port, a valve for controlling the flow of fuel through said inlet port, a fuel tank, means for connecting the fuel tank with the inlet port, of a casing communicating with the opening including a relatively small explosion chamber, an igniting device for firing the charge in said chamber, a valve seat formed in the chamber, a head carried by the casing, a fuel inlet port formed in the head, and a valve including a hollow stem slidably mounted in the casing and arranged to normally fit upon said seat, a second valve carried by the first mentioned valve normally preventing the entrance of fuel from the head into said casing, a valve controlled air inlet port formed in the casing in advance of said head, and a compressed air inlet port formed in the head.
8. A device for starting internal combustion engines and for firing the charges of internal combustion engines comprising a casing having a relatively small explosion chamber therein, means for connecting the casing with a cylinder, a head, a longitudinally extending sleeve connecting the head with the casing, an igniting device carried by the casing for firing the charge, the inner end of the sleeve having a guide seat formed thereon, a valve for normally resting upon said seat, a hollow stem formed on the valve having ports formed in the opposite ends thereof, means for slidably mounting the valve and stem in said sleeve, a pair of inlet ways formed in said head for the reception of fuel and compressed air, a central way for air formed in the sleeve communicating with the interior thereof, a pin carried by said sleeve and extending through the port of said stem nearest said valve, a spring carried by and fitted in said stem and resting against said pin to normally close the valve, ball valves for the inlet ways, a control tube carried by the head and extending into the sleeve, and a valve slidably carried by the stem of the first mentioned valve for fitting in said control tube.
9. In an attachment for internal combustion engines comprising a casing having an explosion chamber therein, a relatively small tapered outlet port communicating with the explosion chamber, an attaching nipple having a tapered way therein for communication with the tapered bore of the casing, means for detachably connecting the casing and attaching nipple together, a head, a sleeve formed longitudinally on the casing and receiving said head, a valve seat formed on the inner end of the sleeve, a valve for seating upon said seat, spring means for normally holding the valve upon its seat, inlet ways formed in the head for fuel and compressed air, and an auxiliary inlet formed in the sleeve, and spaced electrodes carried by the casing on opposite sides of the explosion chamber.
10. In an attachment for internal combustion engines comprising a casing having an explosion chamber therein, a relatively small tapered outlet port communicating with the explosion chamber, an attaching nipple having a tapered way therein for communication with the tapered bore of the casing, means for detachably connecting the casing and attaching nipple together, a head, a sleeve formed longitudinally on the casing and receiving said head, a valve seat formed on the inner end of the sleeve, a valve for seating upon said seat, spring means for normally holding the valve upon its seat, inlet ways formed in the head for fuel and compressed air, an auxiliary inlet formed in the sleeve, spaced electrodes carried by the casing on opposite sides of the explosion chamber, and means for adjusting one of said electrodes in relation to the other electrodes.
11. An attachment for internal combustion engines comprising a casing having an explosion chamber therein, means for introducing fuel and air into the chamber, valves for controlling the flow of air and fuel into the chamber, a pair of spaced insulated electrodes carried by the casing in sparking relation to one another, a central electrode grounded to the casing and in sparking relation to one of said insulated electrodes, and independent ignition circuits for the insulated electrodes.
12. An attachment for internal combustion engines comprising a casing having an explosion chamber therein, means for introducing fuel and air into the chamber, valves for controlling the flow of fuel and air into the chamber, a pair of radially extending sleeves carried by the casing and communicating with the explosion chamber, insulated electrodes fitted in said sleeves extending into the explosion chamber, an adjustable electrode carried by and grounded to the casing, means electrically connecting the casing and one of the insulated electrodes to the ordinary ignition system of an internal combustion engine, an auxiliary ignition system, and means for connecting the auxiliary ignition system with the other insulated electrode and casing.

13. An attachment for internal combustion engines comprising a casing, means for securing the casing to an internal combustion engine, a firing chamber in the internal combustion engine, means for supplying fuel to the chamber, a compressed air tank, means connecting the chamber with the compressed air tank, a manually controlled valve controlling the flow of compressed air to the chamber, a pair of insulated plugs carried by the casing and extended into the chamber, a central electrode grounded to the casing, means electrically connecting one of the insulated electrodes with the ordinary ignition system of an internal combustion engine, an auxiliary ignition system including a battery, a coil, a control switch, means connecting the system with the casing and the other insulated electrode, and means for operating said switch upon movement of said valve for controlling the flow of air to the explosion chamber.
14. An attachment for internal combustion engines comprising a casing having an explosion chamber therein, a longitudinally extending sleeve formed on the casing, a head detachably secured to one end of the sleeve, the opposite end of the sleeve having a valve seat formed thereon communicating with the explosion chamber, a longitudinally sliding valve disposed in the sleeve for fitting upon the seat, a fuel inlet way formed in the upper end of the sleeve, a compressed air inlet way formed in the lower end of the head, a way connecting the fuel inlet way and compressed air way together, a control plug having a longitudinally extending bore and radially extending passageway adjustably carried by said head and extending into the sleeve and communicating respectively with the way in the head and the interior of the sleeve, a gravity opening ball valve for the fuel inlet way, a normally closed ball valve for the compressed air way, a spring pressed valve slidably carried by the first mentioned valve for fitting in the bore of the control plug.
15. An attachment for internal combustion engines comprising a casing having an explosion chamber therein, a longitudinally extending sleeve formed on the upper end of the casing having its forward end communicating with the explosion chamber and provided with a valve seat, a head secured to the outer end of the sleeve, a valve for fitting upon the seat including a longitudinally extending hollow stem having ports formed in the opposite ends thereof, a guide mounted in said sleeve for said valve, air inlet and fuel inlet ways formed in the head, a control plug carried by the head extending into the sleeve, a valve slidably mounted in the stem of the first mentioned valve for fitting in the plug, and an auxiliary air inlet valve carried by the sleeve, and ignition devices carried by the casing.

LEYEL C. HALL.
